BASE COVER FOR AUTOMOBILE RADIO ANTENNAE

Fred P. Berdass, Minneapolis, Minn., assignor to Bermo
Industries, Inc., Minneapolis, Minn., a corporation of
Minnesota

Application August 11, 1954, Serial No. 31,815

Term of patent 3½ years

(Cl. D14—6)

Fig. 1 is a view in side elevation of a base cover for automobile radio antennae showing my new design;

Fig. 2 is a view in perspective;

Fig. 3 is a view in top plan; and

Fig. 4 is a view in front elevation.

The dotted lines in Fig. 1 are for illustrative purposes only.

I claim:

The ornamental design for a base cover for automobile radio antennae, as shown and described.
